UNITED STATES PATENT OFFICE.

FORTONATO C. ZANETTI, OF BRYAN, TEXAS.

COMBINED TOY AND BOTTLE-STOPPER.

SPECIFICATION forming part of Letters Patent No. 251,757, dated January 3, 1882.

Application filed November 19, 1881. (No model.)

To all whom it may concern:

Be it known that I, FORTONATO C. ZANETTI, of Bryan, in the county of Brazos and State of Texas, have invented certain new and useful 5 Improvements in Bottle-Stoppers; and I do hereby declare that the following is a full, clear, and exact description of the invention, which will enable others skilled in the art to which it appertains to make and use the same, reference 10 being had to the accompanying drawings, which form a part of this specification.

Figure 1 is a perspective view. Fig. 2 is a section on line x x , and Fig. 3 is a vertical sectional view of my improved bottle-stopper.

15 Similar letters of reference indicate corresponding parts in all the figures.

This invention relates to stoppers for bottles; and it consists in certain improvements in the same whereby the outpouring fluid may 20 be utilized to set in motion an automaton attached to said stopper, as will be hereinafter fully described, and particularly pointed out in the claims.

In the drawings hereto annexed, A represents the body of the stopper, which consists 25 of a tube closed at the upper end, and provided with a flange, B, below which it has a tapering packing-ring, C, adapting it to be fitted in the mouth of an ordinary bottle. Said packing- 30 ring may be made of cork, rubber, or any other suitable material.

From the upper part of tube A, above flange B, a slotted tube or gutter, D, extends diagonally upward, as shown. Through this gutter, 35 which communicates with the stopper-tube, as shown, the liquid may be readily poured from the bottle. The opening E between the tube A and gutter D may be closed by a suitably-constructed automatic valve, F, which when 40 the bottle is tilted opens so as to permit the fluid to escape, while when the bottle reassumes its vertical position it closes so as to prevent the fluid from evaporating or deteriorating.

G is a suitably-constructed U-shaped bracket, 45 adjustable upon the gutter D by means of lugs H upon its inner sides, which, when the said bracket is slid in position upon the gutter, catch over the edges of the latter, as shown in Fig. 2, thus retaining the said bracket in posi-

tion. Bracket G is provided with bearings for 50 a transverse shaft, I, carrying a paddle-wheel, J, which receives its motion from the fluid poured out through the gutter D. This paddle-wheel is suitably connected with and utilized to operate a suitably-constructed jointed figure 55 or automaton, K—as in the drawings, a bicyclist—which when thus operated may be made to perform many amusing and attractive motions and evolutions. The bracket G being detachable, as shown, enables any number of 60 different automatons—such as locomotives, steamboats, mills, &c.—to be successively attached to the same stopper, thus lessening the expense and increasing the amusement to be derived from the device. This, however, is 65 not necessary, and the bracket G may be made to form an integral part of the gutter D.

Having thus described my invention, I claim and desire to secure by Letters Patent of the United States—

1. A bottle-stopper consisting of a tube, A, closed at the upper end, and having flange B, packing-ring C, and diagonally-upward-projecting gutter D, substantially as and for the purpose set forth.

2. A bottle-stopper consisting of a tube, A, closed at the upper end and having flange B, packing-ring C, diagonally-upward-projecting gutter D, and self-closing valve F, substantially as and for the purpose set forth.

3. The combination, with a bottle-stopper having a gutter for the escape of fluid, of an automaton or jointed figure actuated by a paddle-wheel which is operated by the escaping fluid, substantially as set forth.

4. The bottle-stopper A, having gutter D for the escape of fluid, in combination with the removable U-shaped bracket G, having lugs H, shaft I, paddle-wheel J, and automaton K, substantially as set forth.

In testimony that I claim the foregoing as my own I have hereto affixed my signature in presence of two witnesses.

FORTONATO CLEMENTE ZANETTI.
